RECORD-CONTROLLED ACCUMULATOR

Samuel Brand, Binghamton, N. Y., assignor to
 International Business Machines Corporation,
 New York, N. Y., a corporation of New York

Application January 31, 1939, Serial No. 253,818

4 Claims. (Cl. 235—61.6)

This invention relates to a record controlled machine and more particularly to an accumulator operated by a record sheet having graphical characters positioned in a plurality of columns.

The present invention contemplates reading of the characters by a device of the general type in my copending application Serial No. 253,820, filed on Jan. 31, 1939, now Patent 2,209,107. In the copending application, the characters are each scanned individually and progressively with each of the characters being formed to influence the scanning means at certain times during the scanning thereof in conformity with a code, and means are provided to selectively energize certain work circuits according to the time of influencing of the scanning means.

In the preferred embodiment of the invention which is the basis for the copending application, the characters are described as formed of an electricity conducting substance in a legible variation of conventional shapes. Spaced sensing brushes engage the record sheet which is fed past the brushes to permit scanning of the characters progressively from end to end along a straight line. Consequently, the brushes will be electrically interconnected when they simultaneously encounter connected portions of a character these connected portions comprising index marks distributed in conformance to the value of the character as per a code. Moreover, some or each of the characters may comprise a composite character formed with index marks separate from the body part of the character and positioned along the scanning line for likewise interconnecting the brushes at certain timed intervals during the scanning of the character in conformity with the code. A plurality of work circuits are provided connected through a distributor to a common circuit. An amplifying vacuum tube is in the common circuit and its grid bias is arranged to be changed each time the sensing brushes are interconnected to permit passage of current through the tube. The first brush interconnection by each character causes the distributor to be connected by a one revolution clutch to a shaft geared to the drive shaft of the feeding means, to be thereby operated in timed rate relation thereto. As a result, the distributor will effect selective energization of the work circuits in accordance with the time of interconnection of the brushes by each character, the distributor being disconnected after the scanning of each character.

As pointed out in said copending application, the characters are so formed with relation to the brush spacing that the brushes will be interconnected only at the coded times even though the characters may be irregularly disposed on the record sheet. This feature is of exceptional value

in the present invention as will be obvious as the description proceeds.

The present invention makes use of a record sheet having numerical characters of conductive substance positioned thereon in a plurality of vertical and horizontal columns. A set of sensing brushes is provided for each vertical column and the sheet is fed vertically to permit simultaneous and progressive scanning of each character in a horizontal column. Now the feeding means is connected to a driving motor by a one revolution clutch as in said copending application arranged to halt the feeding means to produce a timed interruption after the scanning of each horizontal column of characters. It will be understood that by vertical feeding of the sheet is meant vertical with respect to the vertical and horizontal columns of characters.

A distributor and an amplifying tube are provided as in said copending application for each set of sensing brushes with each distributor being individually connected to the driving motor by a one revolution clutch as set out above upon the first interconnection of the corresponding brushes by each character. A set of code storage or circuit selecting relays is also provided for each set of sensing brushes and the relays of each set are selectively energized by the corresponding distributors.

An accumulator or entry receiving means of a well-known type is connected in a novel manner with the scanning means and includes an accumulator wheel for each vertical column of numerical characters and a magnet for each wheel to connect it to the driving means. Now each set of storage or circuit selecting relays has a plurality of switches to selectively connect the related accumulator magnet to one of the contacts of an emitter according to the value of the character scanned. The emitter is actuated by the driving means during the timed interruption following the halting of the feeding means, and the magnets will be energized at various times in accordance with the contact to which they are respectively connected. In addition, a master switch is provided for each magnet in series therewith, the switch to be closed by a master relay which is energized upon cooperation of the first index mark of each character with the related scanning unit. The driving means of the accumulator is also arranged to effect deenergization of the storage relays and restarting of the feeding means after operation of the emitter.

It is therefore an object of the present invention to provide an accumulating machine whose operation is controlled by a record sheet having graphical characters positioned in a plurality of vertical and horizontal columns.

It is an additional object of the present invention to provide a machine of the type de-

scribed in which all of the characters in a horizontal column are scanned simultaneously to set up a series of storage devices with means being provided to enter the values of the scanned characters on accumulator wheels under the control of the storage devices.

Another object of the invention is to provide a machine of the type described in which the vertical columns are scanned simultaneously step by step with one character in each column being scanned during each step to effect selective energization of a related set of relays which in turn connect the related accumulator wheel controlling magnet to a contact of the emitter according to the value of the character, the emitter being operative during the interval between steps to energize the magnets at various selected times.

Further objects of the instant invention reside in any novel feature of construction or operation or novel combination of parts present in the embodiment of the invention described and shown in the accompanying drawings.

In the drawings:

Fig. 1 is a plan view of the reading device.

Fig. 2 is a view along line 2—2 of Fig. 1.

Fig. 3 is a view along line 3—3 of Fig. 1.

Fig. 4 is a detailed view of the distributors.

Fig. 5 is a partial view showing the feed clutch as taken along line 5—5 of Fig. 1.

Fig. 6 shows a portion of the record sheet.

Fig. 7 is an enlarged view of a portion of Fig. 6.

Fig. 8 is a chart for use with Figs. 6 and 7.

Fig. 9 is a view of the accumulator mechanism.

Fig. 10 is a time chart.

Figs. 11 and 12 constitute the wiring diagram.

In Fig. 6 is shown a record sheet 20 having characters 21 thereon of electricity conductive substance or material, representing the digits 0 through 9. These characters are variations of a conventional shape and may be formed with a typewriter having type of the desired shape and using conductive ink. It will be understood, of course, that other means may be used to form the characters, and other substances may be used to render the characters conductive. It will be noted that the characters are disposed on the sheet in horizontal and vertical columns, having as many horizontal columns as may be desired. The vertical columns are limited to four in number, but it will become apparent later on that the number of vertical columns may be increased. In other words, the characters on the sheet are arranged to indicate a vertical column of four digit numbers.

Along each margin of the record sheet 20 is a series of pin holes 22 for use in feeding the sheet past the sensing brushes which are located as shown diagrammatically. There are four sets of brushes, each set including a pair of spaced wire brushes 23 and 24 arranged to scan each character progressively from top to bottom along a straight line. Upon simultaneous engagement of the brushes of one set with a connected portion of a character, those brushes will be electrically interconnected. The manner in which such interconnections are used to effect operation of a statistical machine will be pointed out later.

The reading device employing the sensing brushes is shown in Figs. 1 to 5. The electric motor 25 is mounted on a base 26 and is controlled by a manual switch 27. The motor is arranged through gear box 28 to drive shaft 29 which is journaled in frames 30 and 31. The

shaft 29 carries a ratchet 32 which forms a part of a single revolution clutch as shown in Fig. 5. This clutch also includes a disc 33 carried adjacent to the ratchet 32 by a sleeve 34 which is mounted loosely on shaft 29 and has a gear 35 (Fig. 1) secured thereto. A pawl 36 is pivotally mounted on disc 33 and biased toward the ratchet 32 by a spring 37 which extends from one end of the pawl to a pin carried by the disc. The other end of the pawl is shaped similarly to tooth 38 formed on the periphery of the disc 33. These two parts, the tooth and the pawl end, engage the end of a lever 39 which is pivoted on a stud 40 secured to frame 30, and is biased in a clockwise direction against a stop 41 by spring 42. The position of the pawl 36 on the disc 33 is such that, when they are disengaged from the lever 39, the end of the pawl is slightly in advance of the tooth 38. Thus, when the tooth and pawl are engaged by the lever, the pawl will be raised to disconnect the disc from the ratchet. A latch member 43 is pivoted at 44 on lever 39 and biased in clockwise direction by spring 45. The motion of the latch member is limited by a guide pin 46 carried by the member and extending through a slot in lever 39. The latch member 43 is in the same plane as the disc 33 and so arranged that the tooth 38 will be latched between the end of the lever 39 and the member 43.

The opposite end of the lever 39 carries an armature 47 for cooperation with a magnet 48 mounted upon bracket 49. Thus, when the magnet 48 is energized, the lever 39 will be moved to release the pawl 36 and disc 33 allowing the pawl 36 to engage the ratchet 32 and effect revolution of the disc 33. As the disc nears completion of a single revolution, the tooth 38 will raise the latch member 43 and the end of the pawl 36 will strike the lever 39. The pawl will then be raised and disconnected from the ratchet just as the tooth strikes the end of the lever, at which time the latch member drops into place. Consequently, each time the magnet 48 is energized, the gear 35 will be turned one revolution in a clockwise direction.

A pair of intermediate gears 50 and 51 (Figs. 1 and 3) are secured to a shaft 52 which is journaled in frames 30 and 31. The former gear 50 engages gear 35 to be rotated thereby and gear 51 then drives gear 53 with which it is engaged. Gear 53 is secured to shaft 54, journaled in frames 31 and 55. A feed roll 56 is secured to the shaft 54 between the frames and is provided with a number of pins 57 for cooperation with the pin holes 22 in the record sheet 20.

The record sheet 20 is arranged to enter the reading device from the left side as viewed in Fig. 2 and to pass over a table 58 mounted between frames 31 and 55. From the table 58 the sheet passes over the feed roll 56 and out of the right side of the device. A pressure roller 59 (Figs. 1 and 2) is rotatably mounted between levers 60 and 61 which are secured to a rod 62 journaled in frames 31 and 55. Another lever 63 is secured to the rod 62 and extends outside of the device to permit manual raising of the roller 59, the lever 63 being normally biased in a counterclockwise direction by spring 64 to hold the pressure roller 59 firmly against the record sheet. A latch lever 65 is pivotally mounted upon frame 31 and biased against a pin 66 carried by the manual lever 63. The end of the latch lever is so shaped that, upon manual raising of the pressure roller, the pin 66 will drop.

into a notch on the latch lever 65 to hold the pressure roller in position to permit a new record sheet to be inserted in the device. An arm 67 also extends between frames 31 and 55 at the left side of the device and carries a leaf spring 68 which acts to hold the record sheet firmly against the table and to cooperate with the feed roller to maintain the record sheet taut.

The brush sets are mounted above the table 58 so that the brushes will engage the record sheet as it is passed thereover. It will be seen from the wiring diagram that one brush 23 of each set of brushes will be connected to a common source. These brushes 23 are, therefore, mounted on a single plate 69 secured to an insulating block 70. The remaining brushes 24 are mounted on individual conducting strips 71 secured to another insulating block 72. The two insulating blocks are in turn mounted between a pair of plates 73 and 74. A rod 75 extending between the frames 31 and 55 supports one end of these plates, and an adjusting shaft 76 journaled in the frames 31 and 55 supports the other side of the plates. This shaft 76 is threaded for cooperation with a nut 77 carried by plate 74 to effect horizontal movement or adjustment of the brushes upon rotation of the shaft 76 by a hand wheel 78. A spring 79 between plate 73 and frame 55 serves to keep the threads tight.

The position of the brushes and the feed roll are so related that, when the feed roll clutch is latched, the brushes will be positioned midway between two horizontal columns of characters. The movement of the feed roll is so related to the movement of shaft 29 that one revolution of the shaft will cause the sheet to be moved past the brushes to permit scanning of one horizontal column of characters and halted with the brushes midway between the scanned line and the next horizontal line of characters. In this manner, all four digits in a number are simultaneously scanned progressively from top to bottom along a straight vertical line.

As is seen from Fig. 10, the sheet is fed before the emitter has ceased operating, but this feeding merely advances the sheet from the prior stopping point midway between two characters and no character index is scanned until after the emitter has ceased operation.

In addition to the ratchet 32, shaft 29 has a gear 80 (Fig. 1) secured thereto. Another gear 81 is mounted on the end of shaft 82 and is in engagement with the gear 80 thereby being constantly driven in a direction opposite to the rotation of shaft 29, which is assumed to be clockwise as viewed in Fig. 3. The shaft 82 is journaled in frames 31 and 55 and has four ratchets 83 (Fig. 4) secured thereto forming part of four single revolution clutches. These clutches are similar to the clutch described for driving the sheet feed roll and each one includes a sleeve 84 loosely mounted on the shaft 82, a disc 85, a pawl 86, a lever 87, a latch member 88 and an armature 89 carried by the lever 87. Four electromagnets 90 are also mounted in between frames 31 and 55 and are positioned to cooperate with the armatures 89. Thus, when one of these magnets is energized, the corresponding sleeve 84 will be rotated one revolution in a counterclockwise direction as viewed in Fig. 2. Secured to each sleeve 84 is an insulated block 91 which in turn carries a distributor brush 92 (Fig. 2). Five distributor segments 100, 101, 102, 103 and 104 are positioned in a circle concentric with the shaft 82 and are arranged to be successively en-

gaged by the brush 92 upon rotation thereof. The segments are insulated from each other by portions of a supporting member 105 which is secured to the base 26. The parts just described are so related to each other that, when a distributor clutch is latched, the distributor brush 92 will be in contact with segment 100.

In order to understand the operation of the multiple scanning means just described, it will be necessary first to carefully examine Fig. 7. As pointed out hereinbefore, characters 21 are electrically conductive and are to be scanned progressively from top to bottom by the horizontally spaced sensing brushes 23 and 24. It will be seen that both the vertical and diagonal bars of the characters are considerably narrower horizontally than the space between the brushes so that the brushes cannot be electrically interconnected by a simultaneous engagement with a single vertical bar or a single diagonal bar. Further, those diagonal bars which form an acute angle with a vertical bar are disconnected therefrom (see numerals 1 and 4), to avoid interconnection of the brushes by simultaneous engagement with connected diagonal and vertical bars. It now becomes obvious that these characters are so formed and their configuration is such that only the horizontal bars will interconnect the sensing brushes. Since the horizontal bars or index marks are considerably wider than the space between the sensing brushes, it becomes apparent that the characters may be irregularly disposed crosswise of the line of scanning, as may occur in a typewritten record, and still effect interconnection of the sensing brushes by each horizontal bar. It is to be understood that the spacing of the brushes 23 and 24 may be even less than shown as long as they will be interconnected only by the horizontal bars.

For purposes of illustration and explanation only, the characters in Fig. 7 have been divided by horizontal lines spaced along the line of motion of the record sheet and marked in accordance with the corresponding segment controlled by brush 92 when the particular line is under the brushes. It will be recalled that the rate of rotation of the distributor brush and the rate of movement of the sheet have a timed relation since both are driven by the same motor. The space between the horizontal lines is the distance that the sheet will be moved past the sensing brushes in the time that it takes the distributor brush to move from one distributor segment to the next. However, it is to be understood that the distributor brush is not necessarily moved from one segment to the next when the sheet is moved the distance from one horizontal line to the next. It will be explained in connection with the wiring diagram how the first interconnection of the sensing brushes 23 and 24 by a horizontal bar of each character will effect operation of the one revolution clutch resulting in a single revolution of the distributor brush, the size and spacing of the characters allowing a complete revolution before scanning of the next character. In other words, the first horizontal bar of each character will always be encountered by the sensing brushes 23 and 24 while the distributor brush 92 is on segment 100, whereupon the distributor brush will be rotated and after all segments have been contacted thereby, it will be held stationary on segment 100 until the first horizontal bar of the next character is encountered. Examination of the character "0" with regard to the spaced horizontal lines reveals that

the sensing brushes will be interconnected while the distributor brush engages segments 100 and 103. Fig. 8 is a chart giving the segments contacted during brush interconnections for each different character. It will be noted that the combination of segments for each character is different from the rest and the combinations set forth in the chart constitute a code.

As each scanning unit reads a coded character, certain electrical circuits are selectively energized to set up a series of storage relays. Thereafter, an accumulator mechanism is operated under the successive control of the relays of each unit. The accumulator mechanism (Fig. 9) is of a well-known type and therefore a detailed description is not required here. For a detailed description, reference may be made to Patent #1,976,617. The drive shaft 106 may be driven by a motor 107 (Fig. 11) and acts through gears 108 to rotate shaft 109 clockwise. Loosely mounted on shaft 109 are four gears 110, one for each vertical column of numerals on the record sheet. An accumulator wheel 111 loosely mounted on shaft 112 is provided for each gear 110 and is to be driven thereby through gear 113. A magnet 114 is also provided for each gear 110, and each of these magnets may be individually energized at various times during the cycle of the machine. Energization of the magnet 114 attracts the armature 115 to displace the attached lever 116, causing the clutching member 117, slidably mounted on shaft 109, to engage member 118 integral with the gear 110. When thus coupled to the shaft 109, gear 110 drives the accumulator wheel for the remainder of the cycle. At the end of the accumulating cycle, bar 119 is moved by a cam to cause finger 120 to declutch gear 110 from shaft 109. As will be pointed out herein-after, the time of energization of the magnet 114 will depend upon the value of the character scanned. For instance, if an "8" is scanned, the magnet 114 will be energized to effect rotation of the accumulator wheel a sufficient amount to move eight numbers on the wheel successively into reading position. Each gear 113 carries a number of pins 121 which cooperate with fingers 122 to prevent over-throw of the wheels 111 upon release of the clutching element.

The usual carry mechanism is provided with each accumulator wheel and acts, when that wheel passes through zero, to advance the wheel of the next higher order.

A resetting mechanism is provided which includes a magnet 123 arranged to be energized upon closure of key switch 124 (Fig. 11). The magnet 123 effects a single revolution of reset shaft 125 (Fig. 9) in a manner fully described in the aforementioned patent. Gear 126, carried by shaft 125, engages gear 127 to rotate shaft 112. The shaft 112 has a groove running lengthwise thereof which cooperates with a pawl 128 carried by each accumulator wheel to pick up that wheel and reset it to zero.

An emitter (Fig. 11) is associated with the accumulator mechanism and includes a set of interconnecting brushes 130 and 131 mounted for rotation by shaft 106, one of said brushes 130 being constantly in contact with a conducting ring 132 and the other being arranged to successively contact nine conducting segments 133 these contacts being diagrammatically illustrated as compressed into an arc of limited angular extent for simplification only, such contacts actually being distributed around shaft 106, approximately 215 degrees. Four cams 134, 135, 136 and 137 are also

secured to shaft 106 to effect operation of switches 138, 139, 140 and 141 respectively. The first two of these switches, namely, 138 and 139 are connected in series with the emitter and operate to make a circuit after the emitter brush has contacted a segment and to break the circuit before the brush leaves the segment to avoid arcing at the brush. Switches 140 and 141 are in other circuits which are now to be considered.

Referring to Figs. 11 and 12, a source of direct current provides a positive line 142 and a negative line 143. It will be seen that both motors 25 and 107 are connected directly between the lines to run continuously, the former being connected through switch 21. From the timing chart, Fig. 10, it is apparent that one revolution of drive shaft 106 is divided into sixteen equal parts or divisions, parts two through ten indicated as "9" through "1" in Fig. 10 being devoted to item entry using the emitter while scanning occurs during the last six parts and the first division of the next cycle. It will also be noted that due to synchronizing means (not shown) interconnecting motors 25 and 107, the time required by the shaft 106 to rotate from one division to the next is the same as that required by the distributor brush 92 to move from one segment to the next. At the beginning of the scanning period cam 137 closes switch 141 for a short time (Fig. 10) to connect feed clutch magnet 48 between lines 142 and 143. Energization of magnet 48 will operate its related one revolution clutch to feed the record from a point midway between characters to the first character, whereupon a horizontal column of numbers is fed past the multiple scanning means and the record is fed to a point midway between the successive characters, where it is stopped for a predetermined interval of time. Now as previously explained, each character in the horizontal column is scanned by an individual scanning device and consequently the scanning devices have been labeled units, tens, hundreds and thousands to indicate the order scanned thereby.

As previously mentioned, all of the brushes 23 of each scanning unit are connected together and to wire 143. A single battery 144 is used for biasing the grids of the amplifying vacuum tubes 145, one of which is provided for each scanning unit. Line 143 is connected by wires 146 to the cathode of each tube and one side of the battery is also connected to the cathode. The other side of the battery is connected by wire 147 to the grid resistor 148 of each tube. The cathode heaters of the tubes are also connected together in series between lines 142 and 143 and controlled by manual switch 149. Now each time a set of brushes 23 and 24 are interconnected by portions of a character 21, a circuit will be completed from one side of battery 144 through the corresponding resistor 148, the interconnected brushes 24 and 23, a portion of line 143, wire 146 to the cathode side of the battery. Consequently, the grid bias of the corresponding tube will be changed in the present instance it being assumed that current is allowed to pass through the tube while the brushes are interconnected.

When the horizontal column of characters are fed past the sensing units, each set of brushes will scan an individual character. The cathode of each tube is connected to line 143 and the plate is connected to brush 92 of the corresponding distributor. Each of these distributor segments 100, 101, 102, 103 and 104 are connected to line 142 through relays 100a, 101a, 102a, 103a, and 104a respectively, and wire 149. As previously

pointed out, distributor brush 92 will be in contact with segment 100 when the sensing brushes 23 and 24 are first interconnected during the scanning of each character. Energization of relay 100a will result and effect closing of contacts 100b. A circuit is then completed from line 142 through magnet 90, contacts 100b, wire 150 and contacts 140 to line 143, cam 136 having re-closed contacts 140 by this time (Fig. 10). When magnet 90 is thus energized, the corresponding one revolution clutch is operated to start rotation of distributor brush 92. Thereafter, certain of relays 101a, 102a, 103a and 104a will be energized in accordance with the segment contacted by brush 92 at the particular time that the sensing brushes 23 and 24 are interconnected by the character being scanned. In other words, the relays will be selectively energized according to the value of the scanned character as set forth by the code.

Contacts 100c are also closed when relay 100a is energized to complete a circuit from line 143 through contacts 140, wire 150, contacts 100c, wire 151, corresponding master relay 100d to line 142. The resulting energization of the master relay closes contacts 100e and 100f, the former establishing a holding circuit from line 142 through relay 100d, contacts 100e, wire 152 and contacts 140 to line 143, the latter contacts 100f being connected in series with the corresponding accumulator magnet 114.

As one of the relays 101a, 102a, 103a, 104a is energized, it closes the corresponding set of contacts 101b, 102b, 103b, 104b respectively, to complete a holding circuit therefrom from line 142 through wire 149, the relay and contacts, and wire 150 to line 143. The corresponding set of contacts 101c, 102c, 103c, 104c, are also closed to complete a circuit from line 142 through wire 153, the corresponding one of relays 101d, 102d, 103d, 104d, the closed "c" and "b" contacts, wire 150 and contacts 140 to line 143. Relay 101d is arranged to operate three double throw switches comprising contacts 101e and 101f, 101g and 101h, 101j and 101k, with the 101f, 101h and 101k being normally closed. Relay 102d operates two double throw switches comprising contacts 102e and 102f, and 102g and 102h, with 102f and 102h being normally closed. Relay 103d operates three double throw switches 103e and 103f, 103g and 103h, 103j and 103k with 103f, 103h and 103k being normally closed. Relay 104d operates a double throw switch 104e and 104f with 104f normally closed.

All of the double throw switches of each scanning unit are so interconnected with each other and with the emitter segments 133, which are also numbered from 1 through 9, that the selective energization of the storage relays in accordance with the code will operate those switches to connect the line 142 through the corresponding magnet 114, master contacts 100f, wire 154, double throw switches to the segment 133 having the same number as the scanned numerical character. If a "1" has been scanned, the relays 100a and 104a have been energized, the former starting the distributor and the latter effecting opening of contacts 104f and closing of 104e. A connection is then made from wire 154 through contacts 104e, 102f and 101f to the "1" segment 133. If a "2" is scanned, the connection is through contacts 104f, 102g, 101h and 103e to the "2" segment. Similarly, a "3" will make a connection through contacts 104e, 102f and 101e; a "4" through contacts 104f, 102h, 101k and 103k; a "5" through 104f, 102g, and 101g; a "6" through 104e and

102e; a "7" through 104f, 102h, 101j and 103h; an "8" through 104f, 102h, 101j and 103g; and a "9" through 104f, 102g, 101h and 103f. If a "0" is scanned, a connection is made from wire 154 through contacts 104f, 102h, 101k to 103j. But for obvious reasons contacts 103j are not connected to the emitter since the accumulator need not be affected by a zero.

Thus, during the scanning period, each pair of sensing brushes scans a character and selectively sets up a series of storage relays which connects the corresponding accumulator magnet to the desired emitter segment. From the timing chart, it can be seen that regardless of the character scanned, the storage relays will be completely set up by the end of the scanning period and before the interval during which scanning is stopped and the emitter is closing its contacts. It is true that, if one of the scanning units is scanning a "4," the corresponding distributor will not have completed its revolution by the end of the scanning period but there will not be any additional relays energized. For example, if the number "7137" has been scanned, the thousands magnet 114 and the units magnet 114 will be connected through the corresponding switches to the "7" segment; the hundreds magnet 114 is connected to the "1" segment 133; and the tens magnet 114 is connected to the "3" segment 133. After completion of these connections and during the interval between scanning of the characters themselves the emitter brush 131, which is connected to line 143, will start contacting the segments 133 successively starting with the "9" segment. When the "7" segment is contacted, the units and the thousands magnets 114 will be energized to operate the corresponding clutch to effect turning of the units and thousands wheels 111. When the "3" segment is contacted, the tens magnet 114 will be energized and when the "1" segment is reached, the hundreds magnet 114 will be energized. There then remains one more cycle division before any index of any character can be scanned by the brushes and just slightly before this cycle division is reached, contacts 140 (Fig. 10) are opened to deenergize the master relay 100d and effect deenergization of magnets 114. Opening of contacts 140 also releases the holding circuits of all the storage relays. Prior, therefore, to the time that any brushes scan an index mark in the succeeding scanning period, the number "7137" has been added to the reading of the accumulator wheels and they are declutched and latched in place. The contacts 141 were closed before the emitter ceased its operative function, to energize the feed clutch magnet 48 to start feeding of the record from a point midway between succeeding characters and following the termination of the preceding addition (see Fig. 10), there ensues simultaneous scanning of the next horizontal column of characters to be added to the reading of the accumulator wheels.

It is possible, of course, to use other codes than the one set forth herein as fully explained in my copending application Serial No. 253,819, filed Jan. 31, 1939, now Patent 2,209,106. It is also obviously possible to permit the reading of additional vertical columns by increasing the size of the scanning device and the accumulator mechanism.

While there has been shown and described and pointed out the fundamental novel features of the invention as applied to a single modification, it will be understood that various omissions and substitutions and changes in the form and details

of the device illustrated and in its operation may be made by those skilled in the art without departing from the spirit of the invention. It is the intention therefore to be limited only as indicated by the scope of the following claims.

What is claimed is:

1. In a device of the character described controlled by a record sheet having legible characters positioned in a column, each of said characters having portions forming electrically conductive index marks positioned along a single straight line in conformance with a character value code, means for sensing said sheet, a source of energy, means for feeding said sheet step by step an amount at least equal to the extent of the configuration of said characters, respectively, in the direction of said column to cause said marks to successively engage said sensing means at certain times in conformance with said code, means controlling said feeding means to produce a timed interruption between successive feeding steps, an energy controlled storage device, means for causing said successive engagements to control the flow of energy from said source to said storage device at times in accordance with the code value of said sensed character and for causing said device to be conditioned in accordance with said code value, a movable accumulating element, driving means therefor, a magnet associated with said element to regulate the amount of movement thereof, a normally open master switch in series with said magnet, means effective upon the first engagement of said sensing means and an index mark to close said master switch, means operable by said driving means during said interruption to connect said magnet through its master switch to said energy source at a selected time under the control of said storage device, and means operable by said driving means following the operation of said last mentioned means to release said storage device and effect opening of said master switch.

2. In a device of the character described controlled by a record sheet having legible characters positioned in a column, each of said characters having portions forming electrically conductive index marks positioned along a single straight line in conformance with the code character value, means for sensing said sheet, a source of energy, means for feeding said sheet, step by step, an amount at least equal to the extent of the configuration of one of said characters in the direction of said column to cause said marks to successively engage said sensing means at certain times in conformance with said code, means controlling said feeding means to produce a timed interruption between successive feeding steps, a set of relays, a master relay, means controlled by said sensing means and including a distributor operating at a timed rate with respect to the rate of operation of said feeding means for selectively energizing said relays in accordance with the code value of marks sensed and effecting energization of said master relay upon sensing of a character, an accumulator wheel, driving means therefor, a magnet associated with said wheel to regulate the amount of rotation thereof, a normally open master switch in series with said magnet and arranged to be closed upon energization of said master relay, an emitter having a plurality of contacts, each relay of said set of relays being operable to connect said magnet through the master switch to one of said contacts, said emit-

ter being operated by said driving means during said interruption to effect timed energization of each magnet according to the connected contact.

5. 3. In a device of the character described controlled by a record sheet having legible characters positioned in a column, each of said characters having portions forming electrically conductive index marks positioned along a single straight line in conformance with its code character value, means for sensing said sheet, a source of energy, means for feeding said sheet step by step an amount at least equal to the extent of the configuration of one of said characters in the direction of said column to cause said marks to successively engage said sensing means at certain times in accordance with said code, a set of relays, a master relay, a distributor operated intermittently one revolution at a time at a rate proportional to the rate of feeding for selectively energizing the relays of said set in accordance with the code value of marks sensed, means controlled by said sensing means upon the first conditioning thereof by the first index sensed, to initiate operation of said distributor to energize said master relay, an accumulator wheel, driving means for said wheel, a magnet for said wheel to regulate the amount of rotation thereof, a normally open master switch in series with said magnet and arranged to be closed upon energization of said master relay, an emitter having a plurality of contacts, said relays being operable to connect said magnet to one of said contacts, said emitter acting in timed relation to said driving means to effect energization of said magnet at a time depending upon the contact connected.
4. In a device of the character described controlled by a record sheet having legible characters positioned in a column, each of said characters having portions forming electrically conductive index marks positioned along a single straight line in conformance with the code value of said sensed character, means for sensing said sheet, a source of energy, means for feeding said sheet step by step an amount at least equal to the extent of the configuration of one of said characters in the direction of said column to cause said marks to successively engage said sensing means at certain times in accordance with said code, an accumulator wheel, driving means for said wheel, means operated by said driving means to effect starting of said feeding means, an energy controlled storage device, means for causing said successive engagements to control the flow of energy from said source to said device at times in accordance with the code value of said sensed character and for causing said device to be conditioned in accordance with said code value, means for halting said feeding means after the sensing of each character, a magnet associated with said wheel to regulate the amount of rotation thereof, a normally open master switch in series with said magnet, means effective upon sensing of said character to close said master switch, means operable by said driving means to connect said magnet through said master switch to said energy source at a selected time in accordance with said code under the control of said storage device and after halting of said feeding means, and means operated by said driving means to release said storage device and effect opening of said master switch.

SAMUEL BRAND.
